COMBINED PHONOGRAPH AND TUNER

Melvin H. Boldt, Glenview, and David P. Chuboff, North Barrington, Ill., assignors to Zenith Radio Corporation

Filed May 23, 1974, Ser. No. 472,748

Term of patent 7 years

Int. Cl. D14—01

U.S. Cl. D56—4 R

FIG. 1

FIG. 2

FIG. 3

FIG. 4

FIG. 1 is a front, top and right side perspective view of a combined phonograph and tuner showing our new design;

FIG. 2 is a front elevational view;

FIG. 3 is a left side elevational view; and

FIG. 4 is a top plan view.

The rear of the base of the combined phonograph and tuner is plain and unornamented.

We claim:

The ornamental design for a combined phonograph and tuner, substantially as shown and described.
